UNITED STATES PATENT OFFICE.

GEO. H. CORLISS AND ELISHA HARRIS, OF PROVIDENCE, RHODE ISLAND.

FORGING THIMBLES.

Specification of Letters Patent No. 14,280, dated February 19, 1856.

To all whom it may concern:

Be it known that we, G. H. CORLISS and ELISHA HARRIS, of the city and county of Providence and State of Rhode Island, have 5 invented a new and useful Machine for Forging Thimbles for Cordage; and we do hereby declare that the following is a full, clear, and exact description of the same, reference being had to the accompanying drawings, forming part of this specification, in which—

Figures 1 and 2 are vertical sections taken at right angles to each other through the center of that part of the machine by which 15 the form is given to the thimble. Fig. 3 is a longitudinal section through the center of the box of one of the shafts.

Similar letters of reference indicate corresponding parts in the several figures. 20 The main peculiarity of this machine consists in the employment of hammers or squeezers to act upon that side of the piece of iron which is to form the interior of the thimble while that side of the piece which 25 is to form the exterior is in contact with a stationary die or anvil.

To enable others skilled in the art to make and use our invention we will proceed to describe its construction and operation.

30 A, is a strong bed plate supported upon standards B, B, and carrying all the working parts of the machine.

O, is a stationary anvil or die the lowest part of the upper side of which is in the 35 form of a segment of the intended figure of the exterior of the thimble as is illustrated in Figs. 1 and 2, where the anvil is shown in section and a partly formed thimble is shown tinted of a bright red color. In front 40 of this segment formed portion, the anvil rises in the form of an incline plane which is tangential to the segment, as shown in Fig. 2.

C, C, are two shafts arranged to rotate 45 in boxes D, D, on opposite sides of, at equal distances from, and a little higher than the anvil, as will be understood by reference to Fig. 1, the said shafts being geared together by a pair of spur gears d, d, to rotate in opposite directions. At the front extremities of these shafts are two solid eccentrics E, E, which are fitted to the two stocks F, F, to which are secured two hammers or as we prefer to term them "squeezers" a, a, which 50 are intended to act upon the upper side of the piece of iron and to give the form to the

interior of the thimble. The faces of these squeezers are each of the form of a segment of one half of the figure of the interior of the thimble. They are arranged to work at 60 an angle of about 120° to each other and at about 30° to the axis of the thimble. The stocks F, F, do not work in fixed guides but are merely connected at their lower ends with the upper arms b, b, of two elbow levers b b', b b', working on fixed pivots j, j, by which method of guiding them the squeezers are caused to have a peculiar action on the iron which we will presently proceed to explain. The piece of iron of which 70 the thimble is formed consists of a piece of flat bar iron of uniform thickness, and is placed in a suitably heated state upon the inclined plane of the anvil and fed down a suitable distance between the successive operations of the hammers or squeezers by means of a feeder G, which works in a suitable guide under a roller e, and may be pushed down by hand or by a rack and pinion. The eccentrics rotating in the direction 75 of the arrows shown upon them in Fig. 1 bring both the squeezers simultaneously into operation on the iron, and at that point in their revolution when they approach the nearest to the anvil—which point is illustrated in Fig. 1—they bring the squeezers close together upon the top of the iron as shown in Fig. 1. Up to this point in the revolutions of the eccentrics the action of 80 the squeezers is mainly that of bending the iron over the anvil, and there is only a slight squeezing action, but the revolution of the eccentrics beyond this point moves the squeezers apart and drags them down over the face of the iron forcing the lower parts 85 of their faces toward the anvil and producing both a "drawing" and "squeezing" action on the iron at the same time and thus bringing the section of the iron to the crescent form necessary for the section of the 90 thimble. The iron being fed down on the anvil after the successive operations of the squeezers gradually curls up and when the whole length of it has been submitted to the action of the squeezers it has assumed the 95 form of a complete ring.

It may be well here to observe that it is not absolutely necessary for the anvil to have the form of a segment of the external figure of the thimble, but it may be nearly 100 straight longitudinally provided it has the proper transverse sectional form, as if the

squeezers have the proper form the iron will curl up and the ring will be produced in giving the transverse sectional form to the whole length of the iron.

5 The motion of the machine does not require to be stopped for the removal of the finished thimbles but the shafts D, D, rotate continuously one of them being furnished with a fly wheel H, to equalize the motion. In order to take out the thimbles the shafts have to be moved back lengthwise to draw the eccentrics out of the squeezer stocks F, F, and to effect this, they are fitted to be capable of sliding in their 10 boxes D, D, and are both connected by a double fork I, with a sliding rod J, which is fitted in bearings e, e, under the bed plate A. This rod J, has pivoted to it at f, a forked lever K, which during the formation 15 of the thimble, hangs freely some distance in front of the elbow levers b, b, but which when the thimble is finished is taken hold of by the only attendant required to work the machine, who with it pushes the rod J, 20 backward far enough to slide the eccentrics out of the squeezer stocks. This brings the point g, g, of the fork of the lever under the lower arms b', b', of the elbow levers b b', b b'. The upper parts of the 25 squeezer stocks F, F, when the eccentrics are withdrawn, rest on two stationary inclined guides h, h, in front of the boxes D, D, and up these guides the said stocks are caused to slide by the attendant pushing 30 down the end of the lever K, which he still holds. The depression of that end of the said lever causes the points g, g, of the said lever to raise the elbow levers which push up the stocks. The squeezers being by this 35 means moved far enough out of the way, enables the thimble to be taken from the anvil by a hook, a pair of tongs or other 40

suitable implement. When this is done, the attendant raises the front end of the lever K, and the squeezer stocks will slide 45 down the guides h, h, to a position to receive the eccentrics, and he then pulls the lever and draws forward the rod J, thus drawing forward the shafts and causing the eccentrics to enter the stocks F, F, again. 50 In order to enable the eccentrics to slide easily into the stocks, their front faces are chamfered off to concentric circles as shown at i, i, Figs. 1 and 3, by which means they are enabled to enter at any point in their 55 revolution. The machine may also be employed for making welded thimbles. To make those thimbles a welded ring should be first formed of flat iron and then submitted to the action of the machine. 60

What we claim as our invention and desire to secure by Letters Patent, is

1. The employment for forging thimbles, of an anvil, O, and hammers, (a), (a), operating substantially as herein set forth. 65

2. In combination with the arrangement of the shafts of the eccentrics to slide the eccentrics out of the stocks F, F, which carry the hammers or squeezers, we claim the inclined guides h, h, to receive the said stocks after the withdrawal of the eccentrics, and the levers b b', b b', and K, for the movement of the stocks up the said guides to withdraw the hammers or squeezers from the interior of the thimble to admit of its removal from the machine, all arranged operating substantially as herein set forth. 75
